DESIGN FOR A HAT

Eugene R. Weisbender and Richard N. Brown,
Dayton, Ohio

Application September 13, 1943, Serial No. 111,120

Term of patent 3½ years

To all whom it may concern:

Be it known that we, Eugene R. Weisbender and Richard N. Brown, citizens of the United States, residing at Dayton, in the county of Montgomery and State of Ohio, have invented a new, original, and ornamental Design for Hats, of which the following is a specification, reference being had to the accompanying drawing, forming part thereof.

We claim:

The ornamental design for a hat, substantially as shown and described.

EUGENE R. WEISBENDER.
RICHARD N. BROWN.
